UNITED STATES PATENT OFFICE.

HENRY R. HEYL, OF PHILADELPHIA, PENNSYLVANIA, ASSIGNOR TO THE AMERICAN PAPER BOTTLE COMPANY, OF PHILADELPHIA, PENNSYLVANIA, A CORPORATION OF PENNSYLVANIA.

TUBE-CUTTING MACHINE.

1,002,690.

Specification of Letters Patent.

Patented Sept. 5, 1911.

Application filed December 1, 1909. Serial No. 530,723.

To all whom it may concern:

Be it known that I, HENRY R. HEYL, a citizen of the United States, residing in Philadelphia, Pennsylvania, have invented **5** certain Improvements in Tube-Cutting Machines, of which the following is a specification.

My invention relates to certain improvements in means for cutting paper or other **10** tubes into sections.

The object of the invention is to so construct a machine that it will cut a tube, especially a tapered tube, into any number of sections desired, and a further object of the **15** invention is to so construct the mechanism that the tube will be rotated simultaneously with the movement of the cutters into cutting position.

In the accompanying drawing,—Figure 1, **20** is a side elevation of my improved tube cutting machine; Fig. 2, is a plan view; Fig. 3, is an end view; Fig. 4, is an enlarged view partly in section on the line 4—4 Fig. 1; Fig. 5, is a sectional view on the line 5—5 **25** Fig. 4; Fig. 6, is a perspective view showing a detail of the invention; Fig. 7, is a perspective view of one of the cutters; Fig. 8, is a view of the tube blank before cutting; Fig. 9, is a view of the tube blank after **30** cutting, and Figs. 10 and 11 are enlarged sectional views on the line 10—10 Fig. 1, showing the cutters in their two positions.

My invention is particularly adapted for cutting the tubes from which the body portions of paper bottles are made. These **35** tubes are preferably made tapered so that bottles of the same size can be readily nested, but it will be understood that the invention can be used in cutting tubes of an even **40** diameter throughout.

A is a standard, B is a head mounted on the standard and having bearings *b*—*b* for the shaft C. On this shaft, between the bearings is a loose belt pulley *c* and a clutch *c'* by which the pulley may be coupled to the shaft. The shaft C overhangs a considerable distance, as shown, and supports a conical form D.

E is a bracket extending from the head **50** or the base, as desired, and on the outer end of this bracket is a movable bearing *e* having an open socket *e'* to receive the end of the shaft C. This bearing has a handle *e''* by which it can be moved, a stop *e'''* on the **55** extreme end of the bracket E limits the

movement of the bearing in one direction, while the shaft limits the movement of the bearing in the opposite direction. When a cone is placed on the form D or removed from it, then the bracket is dropped, but **60** during the cutting operation the bearing is raised so as to make a rigid connection between the shaft and the bracket. The bracket in the present instance is round and mounted on the bracket is a cutter frame F **65** grooved at *f*—*f* for the flanges of the carriages F', each carriage is arranged to receive a cutter bar *g* having a rotary cutter *g'*, this bar can be adjusted vertically by a set screw *g''* and held in position by a binding screw *g'''* which also confines the carriage to the frame F. **70**

By loosening the screw *g'''* the cutter-bar can be raised or lowered and the carriage can be adjusted longitudinally on the frame to any position desired, after which the screw *g'''* can be tightened, holding the parts in the position to which they are adjusted. In the present instance there are seven cutters and these can be adjusted at will on the **75** frame F. In this instance they are grouped in pairs. By this arrangement the tube blank *x*, Fig. 8, is cut into six sections, forming three body portions *x'*, *x''* and *x'''*, of different size, and rings *y*, *y'* and *y''* **80** which are used as reinforcing bands at one edge of each portion, the rings being slipped onto the body portions and secured by paste or other means. The frame F has a handle *F''* by which it can be turned into and out of **85** operative position.

Pivoted to the head B at *h* is a brake *h'*, which bears against a disk *c''* on the shaft C, Fig. 4, and this brake has an arm *h''* with which the frame comes in contact after the **90** cutters have been moved back clear of the form D, so that the form will be prevented from rotating. A stop *b'* on the head B prevents the frame E from moving beyond a given position after the tube is cut. The **95**

clutch *c'* is moved toward and from the pulley *c* by a slide *n* actuated by a lever *n'* pivoted to the head B and having a pin *n''*, which enters a hole in the slide, Fig. 6. This lever is actuated by a cam *n'''* on the **100** frame F, so that the moment the frame is moved to bring the cutters into action the clutch is moved so that the shaft will be rotated. As soon as the frame is moved, so as to throw the cutters out of action, then **105**

the clutch is disconnected and the shaft remains stationary.

As mentioned above, the main use for which my invention is intended is to cut the body blanks of paper bottles or cups. In the present instance a tube is cut into sections forming bottles of quarts, pints and half pints, and the reinforcing rims for each section. There are afterward assembled 10 and bottomed to form bottles or cups. The tube, as shown in Fig. 8, is made of paper rolled to tubular form and tapered and is placed on the form D and is of such a size as to fit snugly thereon. Then by grasping 15 the handle F² of the frame F, the cutters are moved into acting position against the paper tube and the tube is immediately rotated as the clutch is thrown into gear. The cutters are gradually moved under the 20 tube, making a deep cut which will completely sever the tube, the cutters being adjusted so as to clear the form D. The brake mechanism is so proportioned that it will stop the rotation of the form as soon as the 25 cutters return. The bearing e can then be moved clear of the shaft and the several sections of the tube can be removed from the form and another tube substituted therefor.

As shown in Fig. 10, the adjusting screw 30 g² passes through a slot in a slide g⁴, adjustably attached to the bar g. A lug on the slide is shaped to engage one of a series of notches in the back of the bar, so that an extended adjustment of the bar can be made 35 by shifting the slide g⁴, and delicate adjustments can be made by means of the screw g².

I claim:

1. The combination in a machine for cutting tubes, of a shaft, driving means therefor, a form on the shaft to receive the tube blank, a bracket, a frame pivotally mounted on the bracket, a cutter, carried by the frame, for severing a tube mounted on the 40 form, clutch mechanism through which the shaft is driven, clutch operating means actuated by the pivoted frame so that when the said frame is moved to bring the cutters into action the clutch is thrown so as 45 to connect the shaft with the driving means.

2. The combination of a head, a shaft mounted on the head, a form mounted on the shaft, a bracket projecting from the head, a frame pivotally mounted on the 55 bracket, a series of carriages longitudinally adjustable on the frame, a cutter on each carriage, said frame being movable so that the cutters can be forced in contact with a tube mounted on the form.

3. The combination of a head, a shaft, a form on the shaft, a bracket, a frame pivotally mounted on the bracket and having longitudinal guideways, one or more carriages adapted to the guideways, a cutter-bar 60 adjustably mounted in each carriage,

said frame being so arranged in respect to the form that when moved it will throw the cutters in contact with a tube mounted on the form.

4. The combination of a head, a shaft 70 mounted in the head, a cone secured to the shaft, a bracket secured to the head extending parallel with the cone, a bearing on the outer end of the bracket arranged to detachably engage the shaft, a cutter frame 75 pivotally mounted on the bracket and having cutters arranged to cut a tube mounted on the form.

5. The combination of a head, a shaft 80 mounted in bearings on the head, a form mounted on the overhanging portion of the shaft, a bracket extending parallel with the shaft, a frame pivotally mounted on the bracket, a series of cutter bars carried by the frame, a clutch mechanism and means 85 between the clutch mechanism and the pivoted frame so that when the frame is shifted to throw the cutters into action the shaft will be set in motion.

6. The combination of a head, bearings 90 thereon, a shaft mounted in the bearings, a conical form mounted on the overhanging portion of the shaft, clutch mechanism for throwing the shaft into and out of gear, a 95 bracket, a frame pivotally mounted on the bracket, cutters on said frame, a cam on the frame, a lever actuated by the cam, a slide with which the lever is connected, said slide 100 engaging the clutch so that the shaft will be thrown into gear when the frame is turned to bring the cutters into cutting position.

7. The combination of a head, bearings 105 thereon, a shaft mounted in the bearings, a form mounted on the shaft, a bracket, a frame pivoted to the bracket and having cutters, a brake mechanism for the said shaft, an arm on the brake mechanism extending into position to be actuated by the frame when said frame is moved clear of the cutting position.

8. The combination in a machine for cutting tubes into lengths, of a head, bearings on the head, a shaft adapted to said bearings and overhanging the head, a form mounted 115 on the overhanging portion of the shaft, a fixed bracket projecting from the head and under the shaft, an adjustable bearing pivoted to the bracket and engaging the outer end of the shaft, a frame pivotally mounted 120 on the bracket, a series of carriages adapted to guides on the frame, a vertically adjustable post mounted on each carriage, a rotary cutter carried by each post, means for locking the carriage and the post in the position to which they are adjusted, a handle projecting from the frame, a cam on the frame, clutch mechanism actuated by the cam to throw the shaft into and out of gear, a disk on the shaft, a pivoted brake, a 125 130

lever adapted to contact with the disk and prevent the rotation of the shaft, an arm on the brake, a lever extending in close proximity to the frame so that when the arm is operated it will actuate the brake and stop the rotation of the shaft.

In testimony whereof, I have signed my

name to this specification, in the presence of two subscribing witnesses.

HENRY R. HEYL.
